US0D1054523S

(12) **United States Design Patent** (10) **Patent No.:** **US D1,054,523 S**
(45) **Date of Patent:** **** Dec. 17, 2024**

(54) **INSECT REPELLANT CARTRIDGE**

(71) Applicant: **United Industries Corporation**, Earth City, MO (US)

(72) Inventors: **Kelly Schumaker**, Chesterfield, MO (US); **Hemant S. Betrabet**, Earth City, MO (US); **Amber Martin**, Wentzville, MO (US); **Heather Timm**, Cottleville, MO (US); **Alex J. Wall**, St. Louis, MO (US)

(73) Assignee: **United Industries Corporation**, Earth City, MO (US)

(**) Term: **15 Years**

(21) Appl. No.: **29/757,514**

(22) Filed: **Nov. 6, 2020**

(51) LOC (14) Cl. **22-06**

(52) U.S. Cl.

USPC **D22/122; D22/120**

(57) **CLAIM**

The ornamental design for an insect repellant cartridge as shown and described.

DESCRIPTION

FIG. 1 is top, back perspective view of of an insect repellant cartridge according to the new design, the portion shown in broken lines forming no part of the claimed design, the dashed lines showing indeterminate length and indeterminate height;

FIG. 2 is a back elevation view of the embodiment of FIG. 1;

FIG. 3 is a front elevation view of the embodiment of FIG. 1;

FIG. 4 is a right side elevation view of the embodiment of FIG. 1;

FIG. 5 is a left side elevation view of the embodiment of FIG. 1;

FIG. 6 is a top plan view of the embodiment of FIG. 1;

FIG. 7 is a bottom plan view of the embodiment of FIG. 1;

and,

FIG. 8 is a bottom, front perspective view of the embodiment of FIG. 1.

1 Claim, 8 Drawing Sheets
